SLIDE BUCKLE

Application filed March 17, 1931. Serial No. 523,217.

This invention relates to that class of buckles known as slides and used for adjusting the length of looped straps, webbing and the like, without the penetration of the material by a buckle part.

The invention about to be described is an improvement upon the device disclosed by the Letters Patent Numbered 1,788,664 and issued to the same applicant January 13, 1931.

- 10 The device thus disclosed was a slide buckle comprising a rectangular frame having mounted thereon a fixed or sliding intermediate bar split into strands integrally connected at both ends and both of the strands being formed to together provide spaced humps projecting out of the buckle plane in opposite directions. Such a form of intermediate bar was intended to be distinguishable from the intermediate bar structure comprising two bars as disclosed in an earlier patent Numbered 1,762,263 and issued to the same applicant June 10, 1930, the structure there being a pair of loops connected at one side and free at the opposite side, the intermediate bars integrally extending from the free side across the buckle to the connected side, the peaked humps of one bar alternating with the peaked humps of the other bar to provide spaced peaked humps projecting out of the plane of the buckle in one direction and also spaced peaked humps projecting out of said plane in the opposite direction. The device herein disclosed however is of the single intermediate bar type but comprises a bifurcated end portion of a piece of wire of which the slide buckle is made, the end portion of the wire being split into strands integrally connected at one end, the strands being formed out of the buckle plane to provide spaced humps as in the said previous patents, and therefore the objects of the invention are to provide a reversible slide buckle having a single intermediate bar formed with spaced humps projecting in opposite directions at the same spaced intervals and along planes perpendicular to the plane of the buckle; and to provide a slide buckle of wire structure the wire ends of which are secured to the structure within the plane of the buckle. With these and other objects in view as may become apparent from the within disclosures, the invention consists not only of the particular form herein pointed out and illustrated in the drawings, but readily admits of certain modifications within the scope of what hereinafter may be claimed.
- 15 The character of the invention may be best understood by the reference to one illustrative device embodying the invention and illustrated by the accompanying drawings in which the Figure 1 is an upright elevation of the device; and the Figure 2 is a cross-section upon the dotted line "2-2" of the previous figure.
- 20 The device, as illustrated, is made of wire in a single piece of which an end portion is bifurcated by means of a split longitudinally made therein a substantial distance to provide the strands 1 and 2 integrally connected at one end at which end the wire is then bent at substantially right angles to provide the side portion 3, and again bent at substantially right angles to provide the upper horizontal bar 4 substantially parallel to the strands 1 and 2 of the bifurcated portion, the wire being again bent at substantially right angles to provide the side portion 5 engaged by the free ends of the strands 1 and 2, the wire being again bent at substantially right angles to provide the lower bar 6 substantially parallel to the upper bar 4, and the wire end being bent at substantially right angles to provide the side portion 7 in substantially longitudinal alignment with the side portion 3, the wire extremity engaging within the plane of the buckle the bent portion 8 of the wire structure, the bifurcated portion of the wire providing the intermediate bar 9 of the slide buckle. In forming the intermediate bar 9, the strands 1 and 2 are independently made in undulating form with relatively staggered high points projecting out of the plane of the buckle, each strand being immediately bent, as at 10 and 11, in opposite directions out of said plane, and angularly bent and returned, as at 12 and 13, relatively crossed, as at 14, angularly rebent and returned, as at 15 and 16, and recrossed, as at 17, and angularly rebent and returned, as at 18 and 19, and recrossed, as at 20, and so on throughout the

length of the strands 1 and 2 thereby providing spaced peaked humps, as for instance at 13 and 19, projecting in one and the same direction out of said plane, and, as at 12 and 18, projecting out of said plane in one and the same direction opposite to that of the humps 13 and 19, as better illustrated by the Figure 2, the engaging metal surfaces of the free ends of the strands 1 and 2 and the side bar 5 being united in permanent intimate union, as by welding, brazing or by soldering as at 21, and the engaging metal surfaces of the wire extremity and the structure at the bend 8 being likewise united in permanent intimate union, so that in neither instance can the original character of the surfaces so united be restored by any means effecting the mere separation of the parts, the slide buckle thus being made rigid and indestructible. The distance of the projections out of the buckle plane in one direction equaling the distance of the projections out of said plane in the opposite direction, the slide buckle is reversible in use in that the buckle may be turned completely around from the position illustrated by the Figure 1 so that the upper bar 4 may be in the position of the lower bar 6, or so that the side bar 5 may assume the position of the opposite side portions 3 and 7. The spaced humps 13, 19 and like humps projecting from the buckle plane in one direction, and the spaced humps 12, 18 and like humps projecting from said plane in the opposite direction, provide an acute detour for a strap threaded into the slide buckle in a manner already known to the art. The humps 15, 16 and like humps, although not projecting out of the buckle plane, are formed like the humps 12, 13, 18 and 19, in planes perpendicular to the buckle plane, as illustrated by the Figure 2.

I claim:

1. A reversible slide buckle comprising a frame having horizontal upper, lower and intermediate bars and side structures, the intermediate bar being split into strands integrally connected at one end, and peaked humps provided by both strands, the peaked humps of one strand alternating with the peaked humps of the other strand to provide spaced peaked humps extending in one direction along planes perpendicular to the plane of the buckle and also spaced peaked humps extending in the opposite direction along said perpendicular planes.

2. A reversible slide buckle comprising a rectangular frame having horizontal upper, lower and intermediate bars and side structures, the intermediate bar being split into strands integrally connected at one end, the strands being first bent out of the plane of the buckle, each in opposite directions, and each strand being further bent, relatively crossed and recrossed to together alternately provide spaced peaked humps extending in both

directions along planes perpendicular to the buckle plane.

3. A slide buckle of rectangular form having horizontal upper, lower and intermediate bars and side structures, the intermediate bar being split into strands integrally connected at one end, the strands being angularly bent at intervals, the angular bends of one strand alternating with the angular bends of the other strand to provide spaced peaked humps extending in opposite directions along planes perpendicular to the plane of the buckle. 70

4. A slide buckle of rectangular form having horizontal upper, lower and intermediate bars and side structures, the intermediate bar extending from one side structure to the other side structure and longitudinally split into strands integrally connected at one end, and peaked humps provided by both strands which together provide spaced peaked humps projecting in opposite directions out of the plane of the buckle. 80

5. A slide buckle comprising a rectangular frame having horizontal upper, lower and intermediate bars and side structures, the frame being formed from a piece of wire of which an end portion is split to provide a bifurcated intermediate bar of which both strands integrally extend from one side structure to engage their free ends with the other side structure and the other end portion engages the buckle structure, peaked humps provided by both strands which together provide spaced peaked humps projecting in opposite directions out of the plane of the buckle, means uniting within said plane the engaging metal surfaces of the strands and the side structure in permanent intimate union, and similar means uniting within said plane the engaging metal surfaces of the other wire end and the buckle structure in permanent intimate union. 90

6. A slide buckle comprising a wire structure in the form of a pair of loops arranged in a common plane and separated by an intermediate bar longitudinally split to provide strands integrally connected, each strand immediately being bent in opposite directions out of said plane, and each strand being angularly bent and returned, relatively crossed, 110 angularly rebent and returned and recrossed, repeatedly, the strands thus providing spaced peaked humps extending out of the said plane in both directions, the free wire ends being secured within said plane to the 115 wire structure.

7. A slide buckle comprising a piece of wire bent to form a pair of loops arranged in a common plane and separated by an intermediate bar provided by an end portion of the piece of wire and longitudinally split to provide strands integrally connected, each strand immediately being bent in opposite directions out of said plane, and each strand being angularly bent and returned, relative- 125 130 135

ly crossed, angularly rebent and returned and recrossed, repeatedly, the strands thus providing spaced peaked humps extending out of the said plane in both directions, the metal surfaces of the free wire ends being united in permanent intimate union within said plane to the engaging metal surfaces of the buckle.
